PATTERN CARD CYLINDER FOR JACQUARD LOOMS

Filed April 25, 1935

UNITED STATES PATENT OFFICE

2,045,946

PATTERN CARD CYLINDER FOR
JACQUARD LOOMS

Herbert V. Foster, Providence, R. I., assignor to
Crompton & Knowles Jacquard & Supply Com-
pany, Pawtucket, R. I., a corporation of Mas-
sachusetts

Application April 25, 1935, Serial No. 18,096

3 Claims. (Cl. 139—330)

This invention relates to Jacquard looms and more particularly to the cylinders by which the pattern cards are successively presented to the jacquard needles.

5 In the operation of such looms, it is essential that accurate alignment of the cards and needles be maintained at all times, as otherwise an incorrect fabric may be woven. It has been found difficult to maintain such accurate alignment when 10 the cylinder gudgeons become worn, and the repair or replacement of a worn cylinder has been a matter of considerable difficulty and substantial expense.

15 It is the general object of my invention to provide improvements in the construction of pattern card cylinders for Jacquard looms, by which improvements the useful life of a cylinder may be indefinitely prolonged at negligible expense, and by which improvements worn cylinders can be 20 cheaply and easily restored to satisfactory operative condition.

25 My invention further relates to arrangements and combinations of parts which will be herein-after described and more particularly pointed out in the appended claims.

20 A preferred form of the invention is shown in the drawing, in which

Fig. 1 is a front elevation, partly in section, showing a portion of a jacquard cylinder and bearing embodying my improvements, and

30 Fig. 2 is an end elevation, looking in the direction of the arrow 2 in Fig. 1.

35 Referring to the drawing, I have shown a portion of a jacquard cylinder 10 having a gudgeon 11 fixed in each end thereof. Commonly the cylinder 10 is formed of wood and the gudgeons 11 are firmly secured therein.

40 The cylinder 10 is provided with the usual alignment members 12, one at each corner of the cylinder and cooperating with a pressor member 13 yieldingly forced downward by a spring 14 and effective to hold the cylinder accurately in some one of its four operative positions.

45 In the preferred construction of my invention, I provide each gudgeon 11 with a closely fitting sleeve 20 which may be secured to the gudgeon by a collar 21 fitting over the sleeve and having a set-screw 22 threaded in the collar and extending through an opening in the sleeve to engage the gudgeon 11. The sleeves 20 are preferably 50 formed of hardened steel and are accurately finished both inside and out.

Each sleeve 20 extends into an anti-friction bearing, shown herein as of the roller type and comprising rollers 30 mounted within a hardened

outer ring or runway 31 which in turn is mounted in a casing 32. The casing 32 preferably contains a chamber 33 which may be supplied with lubricant through a suitable pressure connection 34. This lubricant provides efficient lubrication 5 for the roller bearing.

The casing 32 fits closely in an opening 35 in a bearing member 36 and may be secured therein by a set-screw 37 and lock nut 38. The bearing member has a bolt and slot connection with a 10 bracket or stand 40 which in turn is bolted to the jacquard slide shaft, not shown.

The bearing member 36 may be vertically adjusted relative to the bracket 40 by means of an adjusting screw 42 and nut 43, said screw being 15 threaded in an offset projection 44 at the upper end of the bearing member 36. After being vertically adjusted, the bearing member may be secured in adjusted position by a clamping bolt 45. 20

With this construction, it will be evident that the cylinder 10, gudgeons 11 and sleeves 20 rotate as a unit within the rolls 30 or other suitable anti-friction members. The life of the cylinder is 25 greatly prolonged for the following reasons: 25

In the first place, it has been found impractical to provide hardened gudgeons for wooden pattern cylinders and consequently the gudgeons have been subject to relatively rapid wear. With my improved construction, there is no wear on 30 the gudgeons themselves and the hardened sleeves 20 are adapted to resist wear for a long period of time. If, however, a sleeve 20 becomes worn, it may be readily removed and replaced at trifling expense, after which the cylinder is practically 35 as good as new.

Furthermore, I find that the sleeves 20 may be applied to the worn gudgeons of cylinders already in use, as these gudgeons are commonly worn only in certain places and have a sufficient portion of the original contour to accurately center the sleeve thereon. Consequently the restoration of worn cylinders may be accomplished at greatly reduced expense, as compared to the cost of the previous restoration. 45

If the rolls 30 or rings 31 should become worn, these parts also may be replaced at slight expense.

I have thus improved the construction and operation of pattern card cylinders in Jacquard looms and have provided a construction by 50 which repairs may be cheaply and easily accomplished when the same becomes necessary.

Having thus described my invention and the advantages thereof, I do not wish to be limited to the details herein disclosed, otherwise than 55

as set forth in the claims, but what I claim is:—

1. In a Jacquard loom, a pattern card cylinder having end gudgeons, a sleeve for each gudgeon, means to detachably secure said sleeves on said gudgeons and to permit convenient removal and replacement of said sleeves, and an anti-friction bearing surrounding and supporting each sleeve.
2. In a Jacquard loom, a pattern card cylinder having end gudgeons, a sleeve for each gudgeon having a transverse opening therethrough, a collar surrounding each sleeve and having a set-screw extending through said transverse opening and engaging the associated gudgeon, and an

anti-friction bearing surrounding and supporting each sleeve.

3. In a Jacquard loom, a pattern card cylinder having end gudgeons, a sleeve for each gudgeon having a transverse opening therethrough, a collar surrounding each sleeve and having a set-screw extending through said transverse opening and engaging the associated gudgeon, an anti-friction bearing surrounding and supporting each sleeve, and means to removably secure each bearing in operative position. 5 10

HERBERT V. FOSTER.
